UNIVERSAL COMBINATION FUEL AND
VACUUM PUMP

Morris Katcher, New York, N. Y.

Application December 7, 1945, Serial No. 633,333

6 Claims. (Cl. 103—4)

1

This invention relates to a universal combination fuel and vacuum pump for use with internal combustion engines. Motors in use at present are made to suit, in some instances, the location of the fuel pump on the upper level and the vacuum pump on the lower level and on corresponding levels all connections from the fuel tank to the carburetor via the pump as well as connections from the accessories, such as the windshield wiper, to the intake manifold via the pump. In the case of other motors conditions are reversed, the motors and said connections suiting a combined pump in which the fuel pump part is on the bottom and the vacuum pump part on the top. To satisfy both conditions, it has been necessary, heretofore to supply the replacement parts trade with two types of combination pump, one in which the fuel pump part was on top and the other in which the vacuum pump part was on top. To supply the replacement trade with only one type of prior art combination pump would require that in about half the cases, the installation of the pump would become a difficult task requiring an expert as well as extra and possibly special fittings. Accordingly it is an object of the present invention to provide a combination pump which will suit both of the conditions noted above, which pump does not require special skill and fittings to install, no matter which way it must be installed, that is either with the fuel pump on top or the vacuum pump on top. A further object, as an aid to the universality of the pump, is the provision of a detachable mounting or supporting bracket which is of such symmetry that it may be reversed with respect to the engine casing or the pump body. The provision of a plurality of sets of holes in the bracket and corresponding holes in the pump body permits the mounting of the pump on a number of different engines instead of requiring specially holed pumps for said different engines. Such a bracket could be standard for a group of motors, special brackets only being required for groups of motors, instead of individual types of motors.

To make it possible that the pump operate efficiently in reversed positions, provision is made that the inner end of the operating lever is in such operative relation to the means extending between the diaphragms for effecting their strokes and the diaphragms themselves, that it reciprocates or rocks from a mean position which is suitable for either the fuel pump diaphragm or the vacuum pump diaphragm, no matter which diaphragm is on top. The inner end of the operating lever must bear a constant relation to the

2

diaphragms, even if it is necessary that its outer end be varied to suit the driving means of the particular engine with which the pump is to be used. Further, the outer end of the operating lever should also be in a different relation to the driving means or cam where the combination pump is mounted with the fuel pump diaphragm on top than from where said diaphragm is on the bottom of the combination pump.

10 With the type of strainer or filter used, it is necessary that the bowl be on the bottom, so that it would not do to reverse the pump and with it the filter bowl. Accordingly, the overhanging portion of the fuel pump cover, that is the portion which supports the strainer bowl, is made with a certain symmetry of parts, enabling the bowl to be mounted on either side of said cover no matter which way the cover is turned so that the bowl is always on the bottom.

15 20 A further object of the invention resides in the construction of the lost motion connection between the inner end of the operating lever and the means extending between the diaphragms.

25 Other objects and advantages will become apparent upon further study of the description and drawings in which:

Fig. 1 is a front elevation of the combination fuel and vacuum pump.

Fig. 2 is a longitudinal section through the pump taken at right angles to the view of Fig. 1, a portion of the vacuum pump housing, however, being shown in elevation, the vacuum pumping mechanism being below and the fuel pumping mechanism being above.

30 35 Fig. 3 is a sectional plan through the pump taken along the line 3—3 of Fig. 1, substantially at the level of the pivot pin of the operating lever, the strainer being omitted.

40 Fig. 4 is a cross section of the strainer taken at right angles to section 2, and

45 Fig. 5 is a longitudinal section of the pump shown with the vacuum pumping mechanism above, and the fuel pumping mechanism below, a portion of the housing of the vacuum pump being shown in elevation, a different operating lever being used from that shown in Fig. 2.

The pump has a central body portion or intermediate member denoted in its entirety by the numeral 6. In Figs. 1, 2 and 4, the fuel pump cover, denoted in its entirety by the numeral 7, is mounted on the top of intermediate member 6 by means of bolts 8, two of them only being shown in Fig. 1, the rest being omitted for clarity. Flexible diaphragm 9 of the fuel pump is clamped 55 at its edges between flange 10 at the top of the

intermediate member 6 and flange 11 of cover 7 defining fuel pump chamber 49. The central portion of diaphragm 9 is clamped between washers 12 and 13 which are held together by rivet 15 formed on the top of stem 14. Surrounding stem 14 below washer 13 is compression spring 16, the lower end of which abuts washer 31 while its upper end abuts washer 13. A readily removable mounting bracket 17 is held to body portion 6 by means of screws 18 and the bracket in turn is held by bolts 22 to the engine mounting 19, fragmentally shown in dotted lines. Operating lever 20 is pivotally mounted in bracket 17 by means of pin 21, an extension 22 to the bracket on each side thereof being provided as a bearing for the pin. Body portion 6 is recessed to receive extensions 22. A readily removable and changeable mounting bracket with its operating lever permits the use of a standard pump body with different types of motors. Suitable brackets and levers are provided to take up the variation in the motors while the pump body remains standard. It is to be noted that the portion of lever 20 within housing 6 can remain standard, only the outside portion needing to be varied. This type of bracket and lever form the subject of my Patent No. 2,440,175. Lever 20 is formed of two sheet metal arms 23, Fig. 3, joined at their outer end by bridge piece 24, at pivot pin 21 by sleeve 25 and toward stem 14 by rivet 26. At pin 27, which extends through stem 14, lever 20 straddles the stem, an arm 23 coming on each side thereof. Each arm 23 of lever 20, is provided with a slot 28 in which pin 27 operates, said slot being elongated along the longitudinal axis of stem 14 to allow for lost motion of pin 27 with relation to said lever. The upper and lower edges of the inner ends of the arms 23 of lever 20 are provided with horizontally extending flanges 29 and 30. Flanges 29 engage the bottom of washer 31, while flanges 30 engage the top of sleeve 32 in which the lower portion of stem 14 is slidably mounted. Bridge piece 24 at the outer end of lever 20 is forced to ride on the surface of cam or eccentric 33 by the pressure of spring 34 whose upper end engages body portion 6. Cam 33 is mounted on shaft 35 which is usually the cam shaft of the motor.

Supporting or mounting bracket 17 is preferably made symmetrical with reference to a horizontal axis passing at right angles through the longitudinal axis of pin 21 at its center, so that it may be readily reversed with respect to body portion 6.

Vacuum pump diaphragm 39 is held between flange 38 of vacuum pump housing 37 and bottom flange 36 of body portion 6, said flanges being held together by bolts 40. Diaphragm 39 is held between washers 40 and 41, said washers being held together by rivet 42 formed on the bottom of plug 43. Plug 43 is fixed in the lower portion of sleeve 32 by means of pin 44. A spring 45 under initial compression, abuts at its upper end against washer 41 and at its lower end not seen, against vacuum pump housing 37 so that normally diaphragm 39 is moved to its upper position in a suction stroke only until the decrease in pressure in chamber 46 is sufficient to overcome the compression in spring 45.

When lever 20 is rocked by cam 33 so that its end at stem 14 is moved down, flanges 30 on its arms 23 bear down on the top of sleeve 32 forcing down diaphragm 39 for its compression stroke against the pressure of spring 45. As

cam 33 revolves, spring 34 pressing down on bridge piece 24, forces the inner end of lever 20 to swing up releasing sleeve 32 and allowing thereby spring 45 to push up diaphragm 39 for its suction stroke. Vacuum pump housing 37 is provided with an inlet and check valve 47 and an outlet and check valve 48. Inlet 47 is adapted to be connected to the vacuum motor of a windshield wiper, not shown. The suction developed by the vacuum pump cannot exceed that produced by the strength of spring 45. When the pressure in chamber 46 becomes lower than a predetermined amount, spring 45 is prevented from expanding. Under this condition, when lever 20 is rocked in a counter-clockwise direction, flanges 30 rise without corresponding rising of sleeve 32, that is there is lost motion in the connection of lever 20 and said sleeve.

Fuel pump cover 7 forms the upper wall of chamber 49 while its lower wall comprises diaphragm 9. Cover 7 is provided with an overhanging extension for holding glass strainer bowl 58 and providing an inlet passage 51. To the outer end of inlet passage 51 is fastened an inlet connection 52 which leads to the fuel tank, not shown. A stop 53 is set across passage 51, so that liquid entering said passage is blocked against further direct travel through the passage and forced to pass through opening 54 into bowl 50. Opening 54 is threaded for a purpose explained later. Bowl 50 is pressed against gasket 55 by means of bail 56, sleeve 57 and U-headed bolt 87. Pressed between gasket 55 and a recess in cover 7 is annular screen 58. An annular channel 59 is recessed in cover 7 above screen 58, an opening 60 leading from channel 59 into passage 51 on the far side of stop 53. The top of cover 7 for its portion over bowl 50 is substantially a duplicate of its bottom. Opening 61 corresponds to opening 60. Channel 62 corresponds to channel 59. Threaded opening 63 corresponds to threaded opening 54. Screen 64 corresponds to screen 58, and gasket 65 corresponds to gasket 55. When bowl 50 is attached to the bottom of cover 7, its top is closed by plate 66 which is held against gasket 65 by means of bolt 67 screwed into hole 63. The reason for the duplication of the bottom conditions of cover 7 on its top is to be seen in Fig. 5 where the fuel pump mechanism of the combination or dual pump is on the bottom instead of on the top as in Fig. 2. While the dual pump may readily be inverted, and with it cover 7, it is nevertheless necessary that the strainer bowl be kept below inlet passage 51, so that the filtrate from the fuel can drop from the screen by gravity.

The filtered fuel, Fig. 2, passes through opening 60 into passage 51 on the farside of stop 53. From passage 51 the liquid fuel passes through inlet check valve 68 into fuel pump chamber 49 upon the downward or suction stroke of diaphragm 9. Upon the upward or compression stroke of diaphragm 9, the liquid is forced through outlet check valves 69 and 70 in tandem, and from there finally out of outlet 71 to the carburetor, not shown. The use of a pair of outlet check valves, such as shown, has been found by experiment to prevent the fuel from being discharged with pulsations. As is well known in the art, such pulsations are damaging to the carburetor and are uneconomical in the use of the fuel. Such check valves form the subject of the application of William Hicks and myself, Serial No. 619,710, now abandoned.

It is to be noted that springs 16 and 45 act in opposite directions on lever 20. In fact at times, one spring will help the lever overcome the

resistance of the other spring, as just after lever 20 has finished its compression stroke on vacuum pump diaphragm 39 and started to rock in a counter-clockwise direction, spring 45 which had been compressed during the compression stroke will recover, forcing up diaphragm 39 and with it sleeve 32 against lever 20, assisting the latter in pressing against spring 16. In Fig. 2, both diaphragms 9 and 39 are at the upper limit of their stroke, compression stroke for diaphragm 9 and 10 suction stroke for diaphragm 39. This means that the pressure in the fuel line, not shown, between outlet 71 and the carburetor and in fuel pump chamber 49 is less than that required for spring 16 to yield, and that pin 27 is at the upper end 15 of slots 28 in arms 23 of lever 20. It also means that the vacuum created in vacuum pump chamber 46 is not great enough to hold back diaphragm 39 against the force of spring 45 so that sleeve 32 contacts lever 20. Should the pressure in fuel pump chamber 49 in a subsequent compression stroke of diaphragm 9 be great enough to overcome the initial compression in spring 16, the inner end of lever 20 will rise without corresponding rising of stem 14, so that pin 27 will be located 20 in slots 28 below the upper end of said slots. In other words, there will be lost motion between lever 20 and stem 14. Under this condition, upon subsequent clockwise motion of lever 20, spring 16 will help push the lever down against the resistance of spring 45 until the top of slots 28 engage pin 27. The reciprocation of diaphragm 9 by lever 20 through the intermediary of spring 16 is also described in my Patent No. 2,440,175.

When the vacuum created in chamber 46 is 35 sufficient to overcome the expansive force of spring 45, sleeve 32 will not follow lever 20 when it rocks in a counter-clockwise direction. In other words there will be lost motion between lever 20 and sleeve 32. This insures that a vacuum in 40 chamber 46 will not be created below a predetermined absolute pressure.

Both washer 31 and sleeve 32 are guided in their reciprocation by ribs 72 and the inside wall 73. Ribs 72 are formed on the inside of intermediate member 6 of the housing and wall 73 extends between walls 74 of member 6, see Fig. 3. A transverse strip 75 forms a partial wall across the back of intermediate member 6. The space between the bottom of strip 75, that is opening 86, and the top 45 of flange 36 is closed by removable plate 76 which is fastened to strip 75 by screw 77. It is to be noted that intermediate member or portion 6 is substantially symmetrical, as far as its rear face is concerned, about screw 77 in strip 75, so that when the pump is inverted, Fig. 5, plate 76 can be turned so that it extends between strip 75 and flange 10, that is over opening 88. In the particular embodiment of the invention shown, the longitudinal axis of screw 77 is in the same plane 60 as the longitudinal axis of lever pivot pin 21. Drain hole 78 in flange 36 and drain hole 79 in flange 10 are symmetrically placed with respect to pin 21. Likewise mounting bracket 17 has suitable symmetry to enable it to be inverted with respect to engine mounting 19 and intermediate member 6. This holds true, therefore, for the holes in said bracket and the corresponding tapped holes, not seen, in member 6 which screws 18 engage for fastening the bracket to said member. This holds true also for holes 81, through which bolts 82 pass, Fig. 1, for fastening the pump to the engine mounting or casing 19 and also for the pairs of holes 83 and 84, said pairs each being used with bolts 82 instead of holes 81 where engine 65

mounting 19 is provided with holes to correspond. The symmetry of bracket 17 makes it possible to mount it in inverted position on member 6 or on engine casing 19. The symmetry of member 6 makes it possible to invert the pump as shown in Fig. 5, either by inverting the pump as a whole including member 6, or leaving number 6 as shown in Fig. 2 without inversion and mounting the vacuum pump housing 37 and diaphragm 39 on its upper flange 10 and the fuel pump cover 7 and fuel pump diaphragm 9 on its lower flange 36.

Absolute symmetry is not required for the various inversions to be effected, as for example the interior details of member 6 may be varied to a certain extent, that is to say upper rib 72 might differ somewhat from lower rib 72, Fig. 2. The same holds true for walls 73 and 74. Even the diameter of fuel pump diaphragm 9 and the diameter of supporting flange 10 need not be the same respectively as the diameter of vacuum pump diaphragm 39 and the supporting flange 36 in the case where the pump is inverted along with member 6. The desideratum is that the stroke of the inner end of the operating lever, lever 20, Fig. 2, and lever 85, Fig. 5, is symmetrical with the maximum strokes of diaphragms 9 and 39. It is further desirable to have the outer end of the operating levers in such position with respect to cam 33, that there is a direct push exerted by the cam for effecting the suction stroke of fuel pump diaphragm 9 and for effecting the compression stroke of vacuum pump diaphragm 39. Spring 34 effects the return stroke of said levers. For this reason, the outer end of lever 20, with the fuel pump diaphragm 9 on top, Fig. 2, has a different position relatively to its pivotal axis and cam 33 than has the outer end of lever 85, Fig. 5, relatively to its pivotal axis and cam 33 when the fuel pump diaphragm 9 is on the bottom. But regardless of said difference in the relative positions of the outer ends of the operating levers, the stroke of their inner ends should bear a constant relation with the maximum strokes of diaphragms 9 and 39 in order for the pump to be reversible. In order not to upset the desired predetermined pressures in pump chambers 46 and 49 when the pump is reversed, the mean position of the strokes of the inner end of the operating lever should be substantially the same distance from the mean position of the strokes of diaphragm 9 as it is from the mean position of the strokes of diaphragm 39. This holds true, however, only for those strokes of both diaphragms which have their maximum possible amplitude, that is when the compression stroke of diaphragm 9 is not shortened because of pressure in excess of the predetermined pressure in the fuel line to the carburetor and when the suction stroke of diaphragm 39 is not shortened because of a drop in pressure in vacuum chamber 46 below that predetermined for it. Further, it is preferable for reversibility that member 6 be so constructed that a horizontal plane through the axis of pin 21 is the same distance from a horizontal plane containing the top of flange 10, Fig. 2, as a horizontal plane containing the bottom of flange 36.

With the pump in inverted position, as seen in Fig. 5, all the parts can be the same except for lever 85, which, as was explained before, should have such a relationship to cam 33, pivot pin 21 and the means 14 and 32 connecting diaphragms 9 and 39 that cam 33 directly pushes said lever 70 during the suction stroke of fuel pump dia-

phragm 9 and the compression stroke of vacuum pump diaphragm 39. Supporting bracket 17 may or may not be the same depending on its fit to engine mounting 19, but this does not affect the action of the pump.

Owing to the opening in engine casing or mounting 19, through which operating levers 20 and 85 pass, oil from the engine can enter the interior of member 6. For this reason drain holes 78 and 79 are provided in member 6 and drain holes 80 in bracket 17. In Fig. 2, drain hole 78 is used to drain the interior of member 6 back into the engine, while with the pump reversed in Fig. 5, drain hole 79 is used. Plate 76 is set to extend from strip 75 to flange 36 in Fig. 2, and is turned to extend from said strip to flange 10 in Fig. 5. This enables whichever of openings 86 or 88 is at the bottom to be closed in accordance with which way the pump is turned and whichever of said openings coming above strip 75 to be clear. Closing lower opening 86, Fig. 2, prevents the escape of oil from the interior of member 6, while a free upper opening 88 prevents entrapment of air in the interior of said member. The entrapment of air in the interior of member 6 would interfere with the proper functioning of diaphragms 9 and 39.

I claim:

1. A combined fuel and vacuum pump for use with driving means comprising a housing providing a fuel pump chamber and a vacuum pump chamber, a flexible diaphragm within the housing adapted to cooperate with the fuel pump chamber, a second flexible diaphragm within the housing adapted to cooperate with the vacuum pump chamber, a stem fastened to the fuel pump diaphragm and extending toward the vacuum pump diaphragm, and a member fastened to the vacuum pump diaphragm and extending toward the fuel pump diaphragm, an operating lever pivotally mounted on the pump and adapted to be rocked by the driving means, the lever positively engaging the stem for the suction stroke of the fuel pump diaphragm and positively engaging said member for the compression stroke of the vacuum pump diaphragm, said strokes being in opposite directions, a spring located in operative relation to the lever and the stem enabling the lever to press against the spring which in turn moves the stem and diaphragm for the compression stroke of the latter, and a spring engaging the vacuum pump diaphragm and the housing, said latter spring opposing the compression stroke of the latter diaphragm and effecting its vacuum stroke, said springs reacting against the lever in opposed directions.

2. A combined fuel and vacuum pump for use with driving means comprising a housing providing a fuel pump chamber and a vacuum pump chamber, a flexible diaphragm within the housing adapted to cooperate with the fuel pump chamber, a second flexible diaphragm within the housing in spaced relation with the first diaphragm adapted to cooperate with the vacuum pump chamber, means extending between the diaphragms having two portions adapted to have axial motion with respect to each other, said portions being mounted in the housing in substantially axial alignment with each other, one portion being fastened to the fuel pump diaphragm and the other portion being fastened to the vacuum pump diaphragm, an operating lever pivotally mounted on the pump and adapted to be rocked by the driving means, said lever engaging the means extending between the dia-

phragms with a lost motion connection, a spring, mounted on the portion fastened to the fuel pump diaphragm, having one end exert pressure against the lever, and having its other end exert pressure against the fuel pump diaphragm, and another spring having one end engage the housing on the opposite side of the vacuum pump diaphragm from the space between the diaphragms, the other end of the latter spring pressing said portion fastened to the vacuum pump against the lever effecting a positive suction stroke and a positive compression stroke of the fuel pump diaphragm only up to a predetermined increase of pressure in the fuel pump chamber and a positive compression stroke and a suction stroke of the vacuum pump diaphragm only down to a predetermined decrease in pressure in the vacuum pump chamber, said lever engaging each of the portions of the means extending between the diaphragms for at least a portion of the positive stroke of each diaphragm.

3. A combined fuel and vacuum pump for use with driving means comprising a housing providing a fuel pump chamber and a vacuum pump chamber, a flexible diaphragm within the housing adapted to cooperate with the fuel pump chamber, a second flexible diaphragm within the housing in spaced relation with the first diaphragm adapted to cooperate with the vacuum pump chamber, means extending between the diaphragms having two portions adapted to have axial motion with respect to each other, said portions being mounted in the housing in substantially axial alignment with each other, one portion being fastened to the fuel pump diaphragm and the other portion being fastened to the vacuum pump diaphragm, an operating lever pivotally mounted on the pump adapted to have its outer end engage and be rocked by the driving means, the inner end of said lever being provided with a longitudinal slot, the sides of the slot engaging a projection provided on one of said portions, and another part of said inner end engaging the other of said portions, lost motion being provided for in said engaging, effecting a positive suction stroke and a positive compression stroke of the fuel pump diaphragm only up to a predetermined increase in pressure in the fuel pump chamber and a positive compression stroke and a suction stroke of the vacuum pump diaphragm only down to a predetermined decrease in pressure in the vacuum pump chamber.

4. A pump for use with driving means, having a housing providing a fuel pump chamber and a vacuum pump chamber, a flexible diaphragm comprised in a wall of the fuel pump chamber, a second flexible diaphragm comprised in a wall of the vacuum pump chamber, a sleeve fixed at one end to the vacuum pump diaphragm, the other end of the sleeve being free, a stem fixed at one end to the fuel pump diaphragm, the other end of the stem being slidably mounted in the free end of the sleeve, an operating lever pivotally mounted on the pump and adapted to be rocked by the driving means, said lever pulling the stem when rocked in one direction, for moving the stem to produce a suction stroke of the fuel pump diaphragm, releasing the stem when the lever is rocked in the opposite direction, said lever pressing against the sleeve when rocked in said one direction, to produce the compression stroke of the vacuum pump diaphragm, and releasing the sleeve when rocked in said opposite direction, a spring reacting between the lever

and the fuel pump diaphragm enabling the lever to effect the compression stroke of the fuel pump diaphragm, and a spring engaging the vacuum pump diaphragm and the housing, said latter spring opposing the compression stroke of the vacuum pump diaphragm and effecting its vacuum stroke, said springs producing pressure against the lever in opposed directions.

5. A combined fuel and vacuum pump for use with driving means comprising a housing providing a fuel pump chamber and a vacuum pump chamber, a flexible diaphragm within the housing adapted to cooperate with the fuel pump chamber, a second flexible diaphragm within the housing in spaced relation with the first diaphragm, adapted to cooperate with the vacuum pump chamber, means extending between the diaphragms having two portions adapted to have axial motion with respect to each other, one portion being fastened to the fuel pump diaphragm and the other portion being fastened to the vacuum pump diaphragm, an operating lever pivotally mounted on the pump and adapted to be rocked by the driving means, said lever positively engaging the portion fastened to the fuel pump diaphragm 20 for the suction stroke of the fuel pump diaphragm, a spring reacting at one end against the fuel pump diaphragm and at the other against the lever, said lever effecting the compression stroke of the fuel pump diaphragm through the 25 intermediary of the spring, said spring being under sufficient initial stress to produce a positive compression stroke of the fuel pump diaphragm until a predetermined pressure in the fuel pump chamber is exceeded, the lever positively engaging the portion fastened to the vacuum pump diaphragm for the compression stroke of the vacuum pump diaphragm, and a spring engaging the vacuum pump diaphragm and the housing, said latter spring opposing the compression stroke of the vacuum diaphragm and effecting its vacuum stroke, said springs reacting against the lever in opposed directions.

6. A combined fuel and vacuum pump for use with driving means having a housing comprising an intermediate member and a removable cover for each end of said member, the relative construction of the covers with respect to the member enabling them to be fastened to either end of the member, said housing provid-

ing a fuel pump chamber and a vacuum pump chamber, a flexible diaphragm comprised in one wall of the fuel pump chamber, a second flexible diaphragm comprised in one wall of the vacuum pump chamber, the diaphragm being fastened to opposite ends of said member, one of said covers being fastened to said member at one end cooperating with the fuel pump diaphragm to complete the fuel pump chamber and the other of said covers being fastened to said member at the other end, cooperating with the vacuum pump diaphragm to complete the vacuum pump chamber, means extending between the diaphragms and fastened to them, an operating lever pivotally mounted on the member and adapted to be rocked by the driving means, said lever engaging the means extending between the diaphragms for effecting their reciprocation, one of said covers being provided with a lateral extension, a strainer for fuel entering the pump having a bowl depending from said extension, the bowl being fastened to the underside of said extension under an opening therein in communication with the fuel pump chamber, the underside of the extension being formed to engage the rim of the bowl in fluid-tight engagement, said extension being provided with a second opening above the first opening, the second opening also being in communication with the fuel pump chamber, the upper side of said extension being formed also to fit the rim of the bowl for a fluid-tight engagement therewith, and a removable closure fastened to the upper side of said extension in fluid-tight engagement therewith in the place where the rim of the bowl would fit, said closure also fitting said first opening.
